UNITED STATES PATENT OFFICE.

WILLIAM SCHMID, OF BRONSON, MICHIGAN.

CARBURETOR.

Application filed May 28, 1920. Serial No. 384,824.

To all whom it may concern:

Be it known that I, WILLIAM SCHMID, a citizen of the United States, residing at Bronson, county of Branch, State of Michigan, have invented certain new and useful Improvements in Carburetors, of which the following is a specification.

This invention relates to improvements in carburetors.

10 The main objects of this invention are:

First, to provide an improved carburetor in which the fuel, such as liquid hydrocarbon, and the air are efficiently mixed and apportioned throughout the variations in

15 running speeds of the engine.

Second, to provide an improved carburetor in which the apportioning of the fuel delivered may be manually varied as desired.

20 Third, to provide in a carburetor an improved priming means.

Fourth, to provide an improved carburetor having these advantages which is compact and comparatively simple in structure.

25 Further objects, and objects relating to structural details will definitely appear from the detailed description to follow.

I accomplish the objects of my invention 30 by the devices and means described in the following specification. The invention is clearly defined and pointed out in the claims.

A structure which is a preferred embodiment of my invention is clearly illustrated 35 in the accompanying drawing forming a part of this specification, in which:

Fig. I is a side elevation of a structure embodying the features of my invention, the 40 air inlet pipes being broken away.

Fig. II is a vertical section on a line corresponding to line 2—2 of Figs. II^A and IV with the carbureting nozzle in priming position.

45 Fig. II^A is a detail vertical section on a line corresponding to line 2^A—2^A of Figs. II and IV, parts being shown in elevation for convenience in illustration.

Fig. III is a detail vertical section corresponding to that of Fig. II with the suction 50 actuated member raised.

Fig. IV is a horizontal section on a line corresponding to line 4—4 of Fig. II.

55 Fig. V is a detail vertical central section of another embodiment of my invention.

In the drawing similar reference characters refer to similar parts throughout the several views, and the sectional views are taken looking in the direction of the little arrows at the ends of the section lines.

Referring to the drawing, the embodiment of my invention illustrated comprises a tubular body member 1 having a primary air inlet chamber 2 therein. At the upper end the member 1 is provided with a cylinder 3 for the suction actuated member 4 and with an outwardly projecting flange 5. The top member 6 has a secondary air inlet chamber 7 therein and a cylinder mixing chamber member 8 aligned with the cylinder 3, the edges of the cylinder 3 and the member 8 being spaced to provide a secondary air inlet opening 9 for the mixing chamber 10.

75 The top member 6 is provided with a flange 11 for the attachment of the carburetor. The discharge 13 for the mixing chamber 10 is controlled by the throttle valve 14.

80 A connection 15 is provided at the lower end of the primary air chamber 2 so that if desired a hot air supply means may be connected to deliver thereto. A hot air connection 16 is also provided for the secondary air chamber 7. This connection has an opening 17 on its under side provided with the weighted valve 18 so that when the suction exceeds a predetermined amount 85 this valve is opened to admit cold air.

90 The fuel reservoir 19 is mounted on the body member 1, with its upper edge against the flange 5. The fuel nozzle 20 is mounted centrally within the body member 1 which is provided with an inwardly projecting arm 21 having a passage 22 therein communicating with the nozzle.

95 The fuel supply connection 23 is controlled by the valve 24 and its float 25. The fuel nozzle delivers to the carbureting nozzle 26 which is mounted on the fuel nozzle for vertical adjustment thereon and so as to deliver centrally into the mixing chamber. This carbureting nozzle is provided with 100 air inlet ports 27 opening into the primary air inlet chamber and is upwardly tapered to coact with the annular valve 28 on the suction actuated member 4, so that as this valve is raised, the opening is increased.

105 The opening is also increased as the carbureting nozzle is lowered.

110 The carbureting nozzle is controlled by

the lever 29 pivoted at 30 to engage the cross pin 31 of the downwardly projecting arms 32 on the carbureting nozzle—see Fig. II^A.

A coiled spring 33 arranged in the seat 34 on the arm 21 urges the nozzle downward or the pin 31 against the control lever. The stop 35 is provided for the lever, the operating connections for the lever not being illustrated as suitable means will be readily supplied.

The suction actuated member 4 carries the cylindrical or sleeve valve 36 slideable within the mixing chamber member 8 so that as the suction actuated member is raised, the secondary air is admitted to the mixing chamber. The suction actuated member, coacting with the cylinder 3 forms a dash pot preventing chattering of the suction actuated member, a check valve 40 being provided for the dash pot, permitting the suction actuated member to return quite promptly to its initial position but retarding its opening movement.

The tubular part 4' of the suction actuated member 4 in the embodiment shown in Figs. I to IV inclusive embraces a cylindrical part of the nozzle member providing a primary air passage of relatively fixed cross section.

Considering the operation of the carburetor reference will first be had to Fig. II showing the carburetor adjusted for priming purposes so that an internal combustion engine will receive a rich explosive charge, mostly fuel with just sufficient air for atomizing purposes. In this view of the drawing the carbureting nozzle 26 has been raised so that its upper tapered end will cooperate with the opening in the valve 28 in providing practically the minimum restriction for primary air entering the mixing chamber through the valve. The entrance of primary air to the lower end of the valve is constant in its preferred form of construction, but by restricting the outlet of the air from the valve into the mixing chamber increases the depression in the mixing chamber, so that a greater quantity of fuel is lifted from the nozzle for priming or starting purposes, there being just enough air entering the ports 27 for atomizing purposes.

The automobile engine having been primed and started the carbureting nozzle 26 is lowered to its normal position shown in Fig. II^A and by comparing the position of the nozzle in this figure with the priming position shown in Fig. II, it will be noted that the opening of the valve 28 has been enlarged so that the primary air will have greater leeway into the mixing chamber than through the inlet ports 27 of the carbureting nozzle. In consequence of this arrangement of parts there will be a desired admixture of air and fuel for engine op-

erating purposes; idling of the engine being controlled by the throttle 14.

When the valve 28 is raised, as shown in Fig. III there is a secondary supply of air and greater leeway for primary air from the bottom of the valve to enter the mixing chamber. In all instances of nozzle or valve adjustment the supply of primary air at the lower end of the valve remains constant because of the relation of the annular wall of the valve 28 to the annular wall of the nozzle 26, and in adjusting the nozzle for priming purposes it is only a question of reducing the supply of primary air to the mixing chamber by restricting the opening at the valve 28 to produce a rich mixture.

In order that the supply of primary air to the mixing chamber may be varied at the lower end of the valve, the carbureting nozzle has been shown in a modified form illustrated in Figure V with another tapered portion 37 which is adjustable relative to the lower end of the valve and by adjusting the nozzle the passage between the valve and the nozzle may be increased or decreased in area and thus provide means of regulating the proportion of primary air to the fuel.

With the parts thus arranged, I secure a very effective apportioning and mixing of the air and fuel, it being possible to increase the apportioning of fuel by the adjustment of the carbureting nozzle member 26. The air passing through the ports 27, which are always open, mixes with the fuel in the carbureting nozzle and the carbureted air is delivered centrally into the mixing chamber and centrally of the column of air passing the valve 28. The secondary supply of air is delivered through an annular opening 105 so that it is evenly mixed with the carbureted air.

I have illustrated and described my improvements in an embodiment which I consider practical both from the manufacturing and utility standpoints. I have not attempted to illustrate or describe certain modifications and adaptations which I contemplate within the scope of the appended claims as I believe the disclosure made will enable those skilled in the art to which my invention relates to embody or adapt the same as may be desired.

Having thus described my invention, what I claim as new and desire to secure by Letters Patent is:

1. In a carburetor, the combination of a tubular bottom body member having a primary air inlet chamber at its lower end and a cylindrical mixing chamber above said primary air chamber and adapted to receive a secondary supply of air, a fuel nozzle disposed centrally within said primary air inlet chamber, a carbureting nozzle to which said fuel nozzle delivers having

- an upwardly tapered tip delivering centrally within the mixing chamber, said carbureting nozzle being adjustable relative to said fuel nozzle and provided with a plurality of air inlet ports at the base of its tapered portion adjacent the tip of the fuel nozzle, an annular primary air inlet valve slidable within said tubular body member and coacting with the tapered part of said carbureting nozzle, 5 a suction actuated member by which said primary air valve is carried mounted within said cylindrical mixing chamber member which constitutes a cylinder therefor, and means operatable in the primary air inlet 10 chamber of said tubular body member adapted for adjusting said carbureting nozzle.
2. In a carburetor, the combination of a body member having a primary air inlet chamber at its lower end and a mixing chamber member above said primary air chamber, 15 a fuel nozzle disposed centrally within said primary air inlet chamber, a carbureting nozzle to which said fuel nozzle delivers having an upwardly tapered tip delivering centrally within the mixing chamber, said carbureting nozzle having air inlet ports at the base of its tapered portion and adjacent the tip of the fuel nozzle, an annular primary air inlet valve through which the tapered 20 part of said carbureting nozzle extends and coacts therewith, a suction actuated member by which said primary air valve is carried, 25 said carbureting nozzle slidably fitting on said fuel nozzle and adjustable relative to said primary air inlet valve and said fuel nozzle, and means axially of said carbureting nozzle retaining said carbureting nozzle normally lowered relative to said fuel nozzle. 30
3. In a carburetor, the combination of a tubular body member having a mixing chamber, a fuel nozzle, a tapered carbureting nozzle delivering to said mixing chamber and constituting a housing for the tip of said fuel nozzle, said carbureting nozzle being slidable on said fuel nozzle and provided with air inlet ports adjacent the tip of the fuel nozzle, an annular primary air inlet valve slidable in said tubular body and coacting with said tapered carbureting nozzle to regulate the passage of air around the same and thereby control the passage of air through said air inlet ports of said carbureting nozzle, and means operatable axially of said nozzles adapted for sliding said carbureting nozzle relative to said primary air inlet valve. 35
4. In a carburetor, the combination of a mixing chamber, a stationary fuel nozzle, a tapered carbureting nozzle slidable on said fuel nozzle and delivering to said mixing chamber and constituting a housing for the tip of said fuel nozzle, said carbureting nozzle being provided with air inlet ports adjacent the tip of the fuel nozzle, an annular primary air inlet valve coacting with said tapered carbureting nozzle to regulate the passage of air around the same and thereby control the passage of air through said air inlet ports of said carbureting nozzle, a suction actuated member automatically controlling said primary air valve, means in the lower part of said fuel nozzle for sliding said carbureting nozzle in one direction and means for manually adjusting said carbureting nozzle in an opposite direction for varying its relation to said primary air valve. 40
- In witness whereof, I have hereunto set my hand and seal.

WILLIAM SCHMID. [L.S.]
